UNITED STATES PATENT OFFICE.

ALFRED G. F. KUROWSKI, OF BROOKLYN, NEW YORK, ASSIGNOR TO UNDERWOOD ELLIOTT FISHER COMPANY, OF NEW YORK, N. Y., A CORPORATION OF DELAWARE.

TYPEWRITING MACHINE.

Application filed January 18, 1927. Serial No. 161,720.

This invention relates to detachable card-holders to facilitate the typing of short, stiff cards in typewriting machines.

Heretofore, when it was desired to use a standard machine for special card-writing, it was necessary to change the ordinary platen to one having pins fixed thereon, requiring the skill of a mechanic to make the change, and being inconvenient and costly. The platen had to be provided with pins protruding from one end, for engaging a rigid stop-arm on the carriage, so that by means of a card-holder, the pins, and the stop-arm, the cards could be quickly inserted and brought to printing position.

It is desired to render the machine suitable for either card-writing or for ordinary work.

A feature of this invention is the provision of a card-holding attachment which may be easily attached to and detached from any standard typewriter. For this purpose the pins are constructed integral with the card-holder, so that, by attaching or detaching the card-holder, the pins will be simultaneously placed on or removed from the machine.

Another feature of the invention is the provision of a permanent stop-arm, normally held in the path of the pins but swingable out of their path, for allowing the card-holder to be turned to a position for removing it from the machine.

Still another feature of the invention is the provision of means on the card-holder for preventing a pair of tongues formed in the card from catching upon the ink ribbon or the wing-scales, comprising an extension on the card-holder to cover the tongues, thereby holding them close to the platen and preventing them from contacting with any other parts of the typewriter.

Other features and advantages will herein-after appear.

In the accompanying drawings,

Figure 1 is a front elevational view of an Underwood typewriting-machine carriage with the invention applied thereto.

Figure 2 is an end view of Figure 1 with parts broken away to show the invention more clearly.

Figure 3 is a view similar to Figure 2, showing the card inserted to the typing line.

Figure 4 is a perspective view of the card-holder in a detached position.

Figure 5 is a view similar to Figure 1, showing the stop-arm swung out of the path of the

pins and the card-holder moved to a position for detaching it from the machine.

Referring to the drawings a platen 10 is revolvably mounted on a shaft 11 journaled in end plates 12 and 13 of a carriage frame 14. The platen may be rotated by a hand wheel 15 mounted on the shaft 11 or by line-spacing mechanism not shown.

In order to facilitate the writing of short stiff cards 16, a card-holder 17 is provided. The card-holder consists of a thin metal bar 18 extending the length of the platen and curved to conform closely with the periphery of the platen. The bar 18 terminates in forked portions 19 and 20 bent down at right angles, and which, when placed on the machine, straddle flat portions 21, on the platen-shaft 11, adjacent the ends of the platen, so that, as the platen is rotated, the card-holder will be carried therewith. For holding the bar 18 tightly against the platen a hook member 22 is pivotally mounted at 23 to each of the forked portions or plates 19 and 20 and may be swung about its pivot by means of a handle 24 to engage the portion 21 and hold the card-holder in place. The hook member is held in operative or inoperative position by means of a double acting spring 25 attached at one end to a pin 26 on the hook member and at its other end to a pin 27 on the forked portion. The card-holder has an under cut 28 against which the bottom edge of the card 16 is aligned and a projecting finger 29 for aligning the side edges of the cards.

Cards, such as those known as Cardex cards, which are used in the index visible filing system, are provided with tongues 30. To prevent these tongues from catching on any parts of the machine such as the ribbon 31 or wing-scales 32, the card-holder 17 is provided with an extension 33. This extension completely covers the tongues (as shown in Figure 1) and holds them close to the platen, thereby preventing them from protruding into the path of parts of the typewriter.

A card is inserted into the machine by placing its bottom edge under the extension 33 and aligning it against the aligning edge of the under cut 28 and the finger 29, after which the platen is rotated rearwardly carrying the card-holder 17 and card 16 with it. The card is thus fed around the platen and over feed-rolls 34 until its first writing line is in typing position. After having completed the typing on the card, the platen is again rotated to

bring the card and card-holder to a position where the typed card can be removed and a fresh one inserted.

For rendering the platen quickly rotatable to either typing or card-inserting position a pair of positioning members is provided. These members or arresting means are in the form of pins 35 and 36 rigidly mounted on the forked portion 20 of the card-holder 17, and protrude into the path of a stop 37 at the lower end of an arm 37^a mounted in a bracket 38 on the end plate 13 of the carriage-frame 14. When it is desired to use the machine for ordinary work the platen is rotated to Figure 4 position and by releasing the hook members 22 the card-holder 17, with the pins 35 and 36, can be lifted off the platen 10. In order to turn the platen to Figure 4 position, the pins must be able to pass by the stop 37. For this purpose the stop 37 on the arm 37^a is swingably mounted on a pin or stud 39 carried by a pair of ears 40 of the bracket 38. The stop 37 is normally held in the path of the pins or arresting means 35 and 36 by means of a spring 41 on the stud 39, but may be swung out of their path by operation of a finger-piece 42 on the upper end of the arm 37^a. For preventing the spring 41 from swinging the stop 37 too close to the platen and into the path of the handle 24 on the hook member 22, the arm 37^a has its upper portion 43 bent outwardly to abut against the bracket 38 and thereby limit the arm and the stop in their movement towards the platen.

The pin 35 acts as a limiting stop for the hook member 22 when the latter is moved to its ineffective position.

Variations may be resorted to within the scope of the invention, and portions of the improvements may be used without others.

Having thus described my invention, I claim:

1. In a typewriting machine, the combination with a carriage, a platen, and a platen-shaft, of a card-holder including a plate covering a small portion of the platen and extending the full length thereof, forked portions bent at right angles from the ends of said plate, a hook-member on each of the forked portions for fastening the card-holder to the platen, and means carried by one of said forked portions to engage an arm on the carriage for limiting the rotation of the platen in either direction.

2. In a typewriting machine, the combination with a carriage, a platen, and a platen-shaft, of a card-holder including a plate covering a small portion of the platen and extending the full length thereof, forked portions bent at right angles from the ends of said plate, a hook-member on each of the forked portions for fastening the card-holder to the platen, and means carried by one of said forked portions to engage an

arm on the carriage for limiting the rotation of the platen in either direction, said means including pins protruding outwardly from said plate.

3. In a typewriting machine, the combination with a carriage, a platen, and a platen-shaft, of a card-holder including a plate covering a small portion of the platen and extending the full length thereof, forked portions bent at right angles from the ends of said plate, a hook-member on each of the forked portions for fastening the card-holder to the platen, and pins carried by one of said forked portions to engage an arm on the carriage for limiting the rotation of the platen in either direction, said arm being swingable out of the path of said pins, to permit the rotation of the platen to a position for removing the card-holder and pins.

4. In a typewriting machine, the combination with a carriage, a platen, and a platen-shaft, of a card-holder carried on the platen and to rotate therewith, plates on the ends of the card-holder, arresting means carried by one of the plates, and a stop for limiting the rotation of the platen by engaging said arresting means, the stop being movable out of the path of the arresting means for permitting the platen to be rotated a greater distance.

5. In a typewriting machine, the combination with a carriage, a platen, and a platen-shaft, of a card-holder carried on the platen and to rotate therewith, plates on the ends of the card-holder, pins mounted on one of the plates, and a stop for limiting the rotation of the platen by engaging the pins, the stop being swingably mounted in a bracket secured to the platen-frame.

6. In a typewriting machine, the combination with a carriage, a platen, and a platen-shaft, of a card-holder including a plate covering a small portion of the platen and extending the full length thereof, forked portions bent at right angles from the end of said plate, a hook-member on each of the forked portions for engaging the platen-shaft and holding the card-holder to the platen, and pins on one of the forked portions for engaging a stop on the carriage and limiting the rotation of the platen, the whole being removable as a unit from the machine for rendering the machine suitable for ordinary work.

7. In a typewriting machine, the combination with a carriage, a platen, and a platen-shaft, of a card-holder including a plate covering a small portion of the platen and extending the full length thereof, forked portions bent at right angles from the end of said plate, a hook-member on each of the forked portions for engaging the platen-shaft and holding the card-holder to the platen, pins on one of the forked portions for engaging a stop on the carriage and limiting

the rotation of the platen, and a spring for normally holding the stop in the path of the pins, said stop having a finger-piece for swinging it out of the path of the pins, to 5 permit the card-holder to be rotated to a position for removing it from the platen.

8. In a typewriting machine, a card-holder for handling a card having tongues in the lower non-writing field thereof, said

holder including a plate, an undercut extension on the plate for receiving the card, the extension covering the card-tongues, the bottom edge of the undercut serving as a gage for the bottom edge of the card, and a finger protruding outwardly from the plate 10 adjacent the extension, for gaging the side 15 of the card.

ALFRED G. F. KUROWSKI.
